UNITED STATES PATENT OFFICE.

FRANK GUNN FARNHAM, OF HONESDALE, PENNSYLVANIA.

BRUSH.

SPECIFICATION forming part of Letters Patent No. 645,523, dated March 13, 1900.

Application filed March 19, 1898. Serial No. 674,508. (No model.)

To all whom it may concern:

Be it known that I, FRANK GUNN FARNHAM, a citizen of the United States, residing at Honesdale, State of Pennsylvania, have invented certain new and useful Improvements in Brushes, of which the following is a specification.

My invention is designed to provide a very simple and cheap construction of brush for the polishing of metals of all kinds and adapted also for use in glass-polishing.

I have aimed to make a brush equally as efficient, if not more so, as the brushes now used by the trade, but more economical to manufacture, and in attaining this object I use a hub or central piece with what I may term "core-sections" encircling the hub and extending therefrom, and the fiber I arrange in layers separated by thin disks of cloth, wood, or like suitable material, the ends of the fiber layers and interposed disks being held by gluing, while to give still further strength and finish I use outer confining-rings secured by gluing or by gluing and nailing to the core-sections, these rings overlapping the inner ends of the fiber.

In the accompanying drawings, Figure 1 is a sectional view showing a completed brush on the right, but with the fibers removed on the left. Fig. 2 is a plan view of Fig. 1. Fig. 3 is a sectional view of a brush with a taper hub.

Referring to Fig. 1, I use a central hub A, and around this hub I place what I term "core-sections" d', each being preferably made up of veneers secured together, though I do not limit myself in this connection, as each section may be in one piece; but I find that the veneers are stronger and not so liable to warp. The sections are separated centrally by a ring or gasket of rubber g or other flexible material. The fiber B is laid in layers, as shown at the right of Fig. 1, with disks a', of cloth or veneer, between the layers, these disks extending only between the layers of fiber at their inner ends, the outer ends of the fiber being free from separation. The fiber layers and interposed disks or rings are securely held together and to adjacent parts of the brush by glue or other adhesive material. In order to confine the layers of fiber, I use outer rings c', these being secured in any suitable manner, preferably by gluing and

clench-nailing to the core-sections d', with their outer portions overlapping and bearing against the inner ends of the fiber and preferably extending over the fibers a distance equal to the width of the intermediate disks or rings a'. This forms a very efficient brush, simple in construction, and not liable to get out of order. The rubber ring g allows a certain amount of elasticity, and more or less pressure can be exerted in order to bring the fiber layers and the surfaces of the core-sections d' in line.

In the form shown in Fig. 1 I do not place the core-sections together, but at each end of the hub, and interpose between the core-sections d' a series of wooden rings E'. The spacing-disks of cloth or veneer in this form extend back to the hub and between the rings E'.

For small brushes six inches in diameter and under I prefer to have the core-sections d' close together and extend the side rings c' into contact with the hub, as in Fig. 2. The hubs in small brushes I prefer to use without a bushing and taper the hole each way to the center, so as to have them fit various taper spindles on which they are secured. The space E' may be provided with a gasket or ring of rubber or other flexible material.

When the brush is liable to come in contact with water, as in glass-polishing, I clench-nail the rims of the veneered rings c', as shown at n, Fig. 2.

The space 1, Fig. 1, may be filled or not, as desired, the filling serving to balance the brush.

The wood-screws s, Fig. 2, I use to strengthen the construction. I prefer to put them in after the brush is thoroughly seasoned.

I do not confine myself to the number of veneer pieces which may be used in different parts of the construction. For instance, in Fig. 1 the outer rings c' I prefer to have made of three pieces of knife-cut veneers glued together, while the interposed disks or rings may be of cloth or veneer or paper reinforced with cloth. Nor do I confine myself to the kind of brush material, since cloth, felt, or bristles may be substituted for Tampico fiber when necessary. Neither do I confine myself to the kind of material used in making the outer rings and core-sections, as these may be

formed in one piece from compressed wood-pulp without departing from the spirit of my invention.

In some cases, when small brushes varying from two and one-half to five inches in diameter are used, I prefer to employ vulcanized rings or disks in place of three-ply wood veneers *c* if they are likely to get wet.

The hubs may have a bushing 15, as shown in Fig. 1, so as to adapt the brush to spindles of varying diameter, the bushing being removed when larger spindles are to be used.

I claim as my invention—

1. A polishing-brush comprising a hub, confining side rings, core-sections, a series of lay-

ers of fiber glued in place between the confining side rings and separating rings or disks between the layers and glued in place therewith, substantially as described.

2. A polishing-brush comprising a hub, core-sections, a ring or gasket between the sections, outer confining-rings, interposed layers of fiber and disks interposed between the layers, substantially as described.

In testimony whereof I affix my signature in presence of two witnesses.

FRANK GUNN FARNHAM.
